FIG. 4 -

UNITED STATES PATENT OFFICE.

JAMES KANAKARIS, OF TOLEDO, OHIO.

TIME-CONTROLLED PHONOGRAPH.

1,381,644.

Specification of Letters Patent. Patented June 14, 1921.

Application filed November 20, 1920. Serial No. 425,322.

To all whom it may concern:

Be it known that I, JAMES KANAKARIS, a citizen of the United States, and a resident of Toledo, in the county of Lucas and State 5 of Ohio, have made an invention appertaining to Time-Controlled Phonographs; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 My invention has for its object to provide a means for causing a phonograph to operate at any desired time. It particularly has for its object to provide a means that may be used in place of the noisy bell of an alarm 20 clock and so that the user of the device, instead of being awakened by the noise of an alarm clock may be called by the playing of music producible by the phonograph. The instrument moreover may be used in connection 25 with a time controlled mechanism for starting a phonograph from time to time as may be desired to give the pleasure incident to the unexpected production of music after expiration of particular, lengthy, intervals 30 of time.

The invention may be contained in structures of different forms. To illustrate a practical application of the invention, I have shown a structure interconnecting the 35 alarm mechanism of a clock with a phonograph. The structure selected for purposes of illustration is shown in the accompanying drawing.

Figure 1 of the drawings, is a rear end 40 view of the horn of the phonograph which is usually located in the interior of the phonograph casing and the mechanism interconnecting the alarm clock and the phonograph controlling lever. Fig. 2 is a side 45 broken view of the device illustrated in Fig. 1. Fig. 3 is a top broken view of the phonograph showing the disk, table, and the controlling lever. Fig. 4 is a front view of the 50 phonograph horn located in the front of the phonograph showing the front view of the clock used to control the phonograph. Fig. 5 is a view of part of the mechanism which 55 coacts with the alarm spring of the clock to operate the control lever of the phonograph. Fig. 6 is a manually operated control means for interconnecting the actuating

mechanism to cause it to operate the lever. Fig. 7 is a view showing the stop means and looking at the mechanism in an opposite direction from Fig. 5. 60

1 in the figures, is the horn which is made in the usual form and is located in the phonograph box or casing. It communicates at one end 2 with a phonograph or sound reproducing mechanism in the manner well 65 known in the art. The other end 3 is located at the front of the casing and is open. The horn 1 flares toward the open end 3 to magnify the sound produced by the reproducing mechanism of the phonograph. 70

4 is the clock which is supported in the frame 5 consisting of a plurality of cross-bars which are secured in front of the open end of the horn. It may be secured to the casing of the phonograph or it may be secured to the front edge of the horn by suitable means. The winding arbor of the alarm mechanism is connected by a rod 6 to a beveled gear 7 supported in a bearing 8 that is located on a pivoted frame 9. The rod 80 6 protrudes from the horn and extends through an upright portion of the plate 15 that is secured to the horn. The rod is provided with a square end on to which a key 10 may be placed for rotating the rod 6 to 85 wind the alarm spring of the clock. A gear wheel 11 is supported on the shaft 12 which is supported on the side walls of the pivoted frame 9. The gear wheel 7 meshes with the gear wheel 11 when the pivoted frame 9 is 90 located in a certain position. A spring 13 is connected to the shaft 12 and to the frame 9. When, therefore, the gear wheels 7 and 11 are in mesh and the key 10 is rotated, the spring of the alarm clock will not only 95 be wound up but also the spring 13. The two springs thus coact to cause rotation of the shaft 12 when the operation is permitted by the tripping mechanism of the alarm clock. 100

The frame 9 is pivotally supported between ears 14 secured to the plate 15 that extends laterally from the sides of the rear portion of the horn 1. A spring 16 is connected to the horn and to the frame 9 which 105 operates to pull the frame 9 toward the horn 1 and so as to cause the gear wheel to mesh with the gear wheel 7. The frame 9 is provided with a laterally extending ear 17 in which is located a block 18 that is eccentrically mounted on the rod 19. The rod 19 is rotatably supported on the plate 15 and 110

the side of the rear portion of the horn 1 by the step 20 and the bracket 21. The rod 19 is provided with a square end 22 whereby the key 10 may be connected to the rod 19 5 and cause rotation thereof. Rotation of the rod 19 will rotate the block 18 and swing the frame 9 away from the horn against the tension of the spring 16 and so as to disconnect the gear wheels 7 and 11. By this 10 arrangement the alarm spring may be wound to any desired tension and then the spring 13 may be wound upon further rotation of the rod 6 by the operation of the key 10.

The shaft 12 is also connected to a disk 15 23 which operates a sliding frame 24 to which the disk is connected by means of the link 25. The frame 24 is formed of these connecting tubes or sleeves 25 located on the rods 26 that are secured in position between 20 the uprights 27 that are secured to the plate 15. A rod 28 is secured to the sliding frame 24. The rod 28 projects upward and so as to press against the end of the rod 29 which is connected to a pair of sleeves located on a 25 pair of rods 31 that are supported in brackets 32. The brackets 32 are secured to the top of the case 33 and the rod 29 extends through an opening 34 formed in the top of the case and so as to actuate the release lever 30 35 commonly used on phonographs to release the table and permit rotation of the table and of the disk that may be placed on the table to reproduce the music impressed or formed phonographically in the disk.

35 A spring 36 is connected to the rod 29 and to a bracket 37 to cause return movement of the rod 29 and as far as possible to keep the rod in contact with the rod 28. The rod 28 may be provided with a portion 38 which 40 extends at right angles to the body portion of the rod so that contact between the two rods may be assured, since the portion 38 will also extend at right angles to the rod 29.

In order that the disk 23 may be turned to 45 a point such as to place the frame 24 at the rear end of its stroke to permit withdrawal of the rod 29 from the lever 35, a stop 42 is secured to the frame 9 and a pin 41 is connected to a disk 43 located on the shaft 50 12. The alarm spring of the clock 4 may thus be wound to near completion and then the frame 9 may be swung so as to cause the gear wheel 11 to mesh with the gear wheel 7 and upon further operation of the rod 6 55 the spring 13 will not only be wound, but also the rod 28 will be shifted forward and rearwardly to permit the rod 29 to be withdrawn and the table to be locked by the lever 35. The shaft 12 will be rotated nearly 60 360° and until the pin 41 leaves the stop 42 on one side and comes in contact with the stop on the other side. This will push the frame 24 forward and rearward and bring it to the rear end of its stroke. When therefore, the rod 6 is released by the time con-

trolled releasing mechanism of the clock, the spring of the alarm clock will coact with the spring 13 to move the frame 25 rearward to cause the operation of the release lever 35 and to draw it forward. This maintains 70 the rod 29 in its rearwardmost position and consequently out of the way of the lever 35 so that the release lever 35 may be operated at any time notwithstanding the fact that the phonograph is provided with a means 75 for also operating the lever by a time controlled mechanism.

The frame 5 extending across the front of the horn may be provided with a door 45 to make the back accessible for setting the 80 clock either as to time or as to starting the phonograph. The cross-bars of the door are arranged in the same manner that the cross-bars of the frame are arranged. It has a side rod 48 that fits into short tubes 46 that 85 are secured to the frame 5. The door is held closed by the operation of the spring 47.

I claim:

1. In combination with a phonograph having a release lever and an alarm clock having a time controlled mechanism for releasing the alarm, a spring, a shaft for supporting the spring and connected to a turn table, mechanism interconnecting the spring and the alarm mechanism of the clock for releasing the spring upon the operation of the time controlled mechanism, and a slideable frame operated by the spring and interconnecting the spring and the lever of the turn table.

2. In combination with a phonograph having a release lever and an alarm clock having a time controlled mechanism for releasing the alarm, a frame, a shaft located in the frame, a spring connected to the shaft, 105 a stop connected to the shaft, mechanism interconnecting the shaft and the release lever of the phonograph and operated by the spring between the limitations of the stop.

3. In combination with a phonograph having a release lever and an alarm clock having a time controlled mechanism for releasing the alarm, a rod connected to the alarm mechanism of a clock for winding the alarm spring of the clock, a gear wheel connected 115 to the rod, a gear wheel meshing with the first named gear wheel, a pivoted frame, a shaft for supporting the second named gear wheel and located in the frame, a spring connected to the shaft, a stop connected to the shaft for limiting the rotation of the shaft to substantially 360°, means interconnecting the shaft and the release lever of the phonograph for moving the lever to release the phonograph and to withdraw the 120 said means from the lever.

4. In combination with a phonograph having a release lever and an alarm clock having a time controlled mechanism for releasing the alarm, a rod connected to the alarm 130

mechanism of a clock for winding the alarm spring of the clock, a gear wheel connected to the rod, a gear wheel meshing with the first named gear wheel, a pivoted frame, a 5 shaft for supporting the second named gear wheel and located in the frame, a spring connected to the shaft, a stop connected to the shaft for limiting the rotation of the

shaft to substantially 360° , slidable means interconnecting the shaft and the release lever of the phonograph for moving the lever to release the phonograph and to withdraw the said slidable means from the lever. 10

In testimony whereof I have hereunto signed my name to this specification.

JAMES KANAKARIS.
